D. WORONZOFF.
ADVANCE ORDER DEVICE.
APPLICATION FILED SEPT. 29, 1920.

1,381,609.

Patented June 14, 1921.

Fig. 1.

PARTS	CODE NUMBERS	MENU	PRICES
A	1	Soup	10¢
	20	Prime Roast of Beef.	25¢
B	40	Soda Crackers	15¢
	60	Graham Crackers.	15¢
C	2	Spaghetti.	10¢
	4	Green Peas.	10¢
D	8	Baked Potato	10¢
	20	Ginger Bread.	10¢
D	40	Lemon Ice Cream.	10¢
E	1	Milk.	5¢
	2	Coffee.	5¢
E	4	Tea.	5¢
	8	Buttermilk.	5¢
F	a	Bread	
	b	Butter.	

To Order: Add Red and blue code numbers - call off both totals, with a or b, or both, for Bread and Butter.

UNITED STATES PATENT OFFICE.

DIONYSIE WORONZOFF, OF NEW YORK, N. Y.

ADVANCE-ORDER DEVICE.

1,381,609.

Specification of Letters Patent. Patented June 14, 1921.

Application filed September 29, 1920. Serial No. 413,545.

To all whom it may concern:

Be it known that I, DIONYSIE WORONZOFF, a citizen of the United States, residing at New York, in the county and State of New York, have invented certain new and useful Improvements in Advance-Order Devices, of which the following is a full, clear, and exact specification.

This invention relates to an advance order device for use in industrial restaurants where meals are furnished to employees either free or for a small charge, and the object of the invention is to avoid waste of food which now occurs because as a rule it is impossible to predict the amount of particular foods or the number of dishes of each food that will be used, and as a consequence the unconsumed food must either be kept over or must be destroyed.

20 The present device may be used alone or with the food order card patented by me on March 4, 1919 No. 1,296,149. This food order card has been successfully used in restaurants where waiters are employed, but as 25 the modern industrial restaurants are at present turning to the "self-service" plan the present order device, as set forth in this application, is designed to meet the requirements of this plan.

30 The invention will be first hereinafter described in connection with the accompanying drawings, which constitute part of this specification, and then more specifically defined in the claims at the end of the description.

35 In the accompanying drawings, wherein similar reference characters are used to designate corresponding parts throughout the several views:—

40 Figure 1 is an elevation of a menu card designed to be used as a part of this advance order device, and

45 Fig. 2 is a plan view of a plurality of check strips also forming a part of the device.

As shown in the drawings, this invention includes the use of menu cards divided into separate parts and groups of parts, each part being designated by a distinctive letter 50 or other character and such designating letters or characters of one group being of the same color and differing from the color of every other group. Each item of food on the menu, included in all of the several parts 55 is designated by a code number or indicia

which is different from every other code number or indicia and is capable of being combined with other code numbers or indicia to form a code by which the particular combination of food orders having said combined code numbers or indicia may be recognized. A separate code, or combination of code numbers or indicia, is preferably used for each group of parts of the menu, and letters as well as numbers 60 may be used in either or any of the parts or groups to designate foods if desired. In connection with said menu cards strips of checks are employed, one strip to correspond with each possible combination of code numbers or indicia making up different codes, and in practice the persons to be fed are furnished with the menus sometimes in advance of the preparation of the meal, for instance, on the previous day, and are asked to make 65 their selections for the next day or meal, giving their selections in code combinations of code numbers. As each person announces his selections in this way a check for such code combination from the corresponding 70 strip is issued to him so that upon presentation of said check by him at the next meal time he may receive the foods desired. By noting the number of checks removed and distributed in this way from each strip and 75 separating the code combinations into their constituent code numbers or indicia the exact number of orders or dishes of each food to be prepared may be readily determined 80 and the preparation of extra orders or 85 dishes, which would not be used, thus avoided. The checks of each strip are preferably serially numbered to facilitate the determination of the number of checks given 90 out on the advance order for each meal. 95

Referring more particularly to the drawings, in Fig. 1 the menu card is designated 1 and is divided by a double transverse line 2 into an upper section or group 3 and a lower section or group 4. The upper section or 100 group 3 is further divided by single transverse lines 5 into parts 6 each designated by a different letter, those shown being "A," "B," and "C," and arranged in a column 7 at the extreme left of the card. In another column 8 arranged next to said column 7 for the part indicia or letters there are arranged code numbers 9 designating the several articles of food written or printed in a central column 10 of the card. The prices 110

of the foods, where charges are made therefor, may be indicated in a column 11 at the right of the card.

The lower section or group 4 of the menu is divided by single transverse lines 12 into parts 13 similar to the parts 6 of the upper section or group and similarly designated by different letters, namely, "D", "E" and "F". The columns 7, 8, 10 and 11 extend down through the lower section or group as continuations of those of the upper section or group, and code numbers 9 are applied to each of the articles of food in said lower section or group.

15 The letters indicating the parts of the upper group are shown colored red, while the letters indicating the parts of the lower group are colored blue, but any other distinctive colors may be used if preferred. The letters for the parts of one group should, however, be differently colored from those indicating the parts of the other group. If desired, the number of parts in each group as well as the number of groups on the menu 25 may be varied to suit requirements. The code numbers or indicia may also be colored to agree with the letters indicating the parts of the respective groups if desired, or the code numbers may be colored and said letters printed in the same color throughout the menu.

The code or combination of code numbers must not be a code number itself and a code number must not be the sum of other code 35 numbers. With these restrictions, any numbers may be selected for use as code numbers. These rules apply to each group separately, so that the same code numbers may be repeated in different groups, if desired, 40 inasmuch as a separate code or combination of code numbers is designed to be employed for each group.

When the menu is divided into two groups, as shown in the drawings, two codes 45 or combinations of code numbers are printed on the checks 130 of the several strips 14 illustrated in Fig. 2, said codes being suitably separated from one another as by a dash as shown, and being arranged in the 50 order the groups occupy on the menu. As already stated, the checks of each strip 14 are preferably serially numbered as at 15. As illustrated bread and butter are designated by letters instead of numbers, but code 55 numbers may be used therefor if desired. The menu may also contain suitable instructions as to the use of the advance order device, as suggested in the space 16 at the bottom of the card in Fig. 1.

60 The three strips of checks illustrated by way of example in Fig. 2 bear codes indicating respectively that soup (1), roast beef (20) and spaghetti (2) in the first group, and gingerbread (20), milk (1), bread (a) 65 and butter (b) in the second group are de-

sired by one or more persons, while another set of persons desire soup (1), peas (4) and soda crackers (40) in the first group, and ice cream (40), coffee (2) and bread (a) in the second group, while still other persons 70 desire soup (1), graham crackers (60) and baked potato (8) in the first group, and gingerbread (20), buttermilk (8), bread (a) and butter (b) in the second group. It will readily be seen that the sums of the code 75 numbers in each of these instances constitute the codes printed on the several strips of checks shown. For instance, taking the first or top strip in Fig. 2, the first code "23" 80 is the sum of the code numbers (1), (2) and (20) which in the first group are applied to soup, spaghetti and roast beef, while the second code "21ab" on said first strip of checks is the sum of the code numbers or indicia (20), (1), (a) and (b) which in the 85 second group on the menu represent gingerbread, milk, bread and butter.

Having thus described my invention, what I claim as new and desire to secure by Letters Patent of the United States is:— 90

1. In an advance order device, the combination with a menu having articles of food shown thereon and code indicia designating said respective foods, of checks bearing codes comprising the sums of certain of the code 95 indicia on the menu for the purpose specified.

2. In an advance order device, the combination with a menu having a plurality of groups of foods shown thereon and code indicia designating said respective foods, of checks bearing a plurality of codes corresponding to the groups of foods on the menu, each code on said checks comprising the sum of certain code indicia in a different group 100 on the menu for the purposes specified.

3. In an advance order device, the combination with a menu having a plurality of groups of foods shown thereon and code indicia designating said respective foods, each 110 group having indicia of a different color from the other or others, of checks bearing a plurality of codes corresponding to the groups of foods on the menu, each code on said checks comprising the sum of certain 115 code indicia in a different group on the menu for the purposes specified.

4. In an advance order device, the combination with a menu having a plurality of groups of foods shown thereon and code 120 numbers designating said respective foods, each group being subdivided into parts having indicia of a different color than those of another group, of checks bearing a plurality of codes corresponding to the groups of foods 125 on the menu, each code on the checks comprising the sum of certain code numbers in a different group on the menu for the purpose specified.

5. In an advance order device, the combi- 130

- nation with a menu having a plurality of groups of foods shown thereon and code numbers designating said respective foods and capable of being combined to form distinctive codes, of a plurality of sets of checks each bearing different codes constituting different combinations of the code numbers in the several groups on the menu for the purpose specified.
- 5 10 6. In an advance order device, the combination with a menu having different foods shown thereon and code numbers designating said respective foods, said code numbers being capable of combination into distinctive codes, of a plurality of sets of checks 15 each bearing different codes constituting different combinations of the code numbers on the menu for the purpose specified.

In testimony whereof I have signed my name to this specification.

DIONYSIE WORONZOFF.
